COMBINED PICTURE FRAME AND ILLUMINABLE SUPPORT THEREFOR

Carl D'Amato, 8784 23rd Ave.,
Bronx, N.Y. 11232

Filed Dec. 12, 1968, Ser. No. 14,942

Term of patent 14 years

Int. Cl. D6—06

U.S. Cl. D29—20

Fig. 1

Fig. 4

Fig. 2

Fig. 3

FIGURE 1 is a perspective view of a combined picture frame and illuminable support therefor, embodying my new design,

FIG. 2 is a front elevational view thereof,

FIG. 3 is a side elevational view thereof,

FIG. 4 is a perspective view thereof,

FIG. 5 is another embodiment of the combined picture frame and illuminable support therefor shown in FIG. 1 wherein the picture frame is held in the palm of the hand-like support,

FIG. 6 is a front elevational view thereof,

FIG. 7 is a side elevational view thereof, and

FIG. 8 is a top plan view thereof.

I claim:

The ornamental design for a combined picture frame and illuminable support therefor, substantially as shown and described.
